UNITED STATES PATENT OFFICE.

ARTHUR E. SMALL, OF OAK PARK, ILLINOIS, ASSIGNOR TO UNION METAL PRODUCTS COMPANY, OF CHICAGO, ILLINOIS, A CORPORATION OF ILLINOIS.

CAR-COUPLER-CENTERING DEVICE.

Application filed November 12, 1925. Serial No. 68,662.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

The invention relates to devices for retaining a railway car coupler adjacent the longitudinal center line of the car. Such a device assures proper coupling and transmits the impact blow, due to the coupling of car, directly to the coupler shank and to the draft gear without causing lateral stress in the coupler head or shank, thus reducing broken coupler knuckles and guard arms. Such a device eliminates the necessity of trainmen going between the cars to move the coupler to such a position that it will couple upon impact with another coupler. This feature reduces accidents to trainmen and also minimizes the time required to couple cars.

In the drawings:

The left half of Fig. 1 shows a part of a railway car with my device applied thereon. The right half of Fig. 1 shows a section on line 1—1 of Fig. 2.

Fig. 2 shows a side elevation of Fig. 1.

Fig. 3 is similar to the right half of Fig. 1 and shows the coupler out of normal position.

The striking casting 1 is attached to the center sills 2 in the usual manner and is provided with a tread 3. The coupler 4 rests upon the carriage 5 and is held in the proper relation thereto by the lugs 6. The carriage is provided with a tread 7. Oval shaped rollers 8 are positioned between and engage the tread on the striking casting and the tread on the carriage.

Fig. 1 shows the coupler and the device in normal position with the minor axis of the roller positioned vertically. When the coupler (and carriage) moves laterally in either direction the oval roller assumes the position similar to that shown in Fig. 3 so that the contacting surface of the roller with the striking casting is not in line with the contacting surface of the roller with the carriage, therefore, the eccentric load of the coupler and its associated parts tends to return the roller to its normal position and to carry the carriage with it; in other words, return the coupler to the longitudinal center

of the car. Furthermore, with the oval roller this eccentricity is increased as the lateral movement of the coupler is increased whereby the further the coupler is away from its central normal portion the greater is its tendency to return thereto. The minor axis of the oval roller is normally positioned vertically so that the eccentric load causes the roller (and the coupler) to return to its normal central position.

The treads on the striking casting and carriage, respectively, may be provided with racks and the oval roller may be provided with teeth which engage the racks to prevent slippage. Any other means to prevent slippage between the treads and the roller may be employed and still come within the broader claims of this invention.

When teeth are used, as above described and illustrated, their depth is made greater than the vertical distance between the top of the coupler and the underside of the striking casting so that when the device is assembled and the coupler is in position thereon, it is impossible for the carriage to move upwardly far enough to permit the teeth of the roller to become disengaged from the rack on the striking casting.

When teeth are used it is preferable to position a tooth 10 on the coupler carriage and a tooth 11 on the car member in vertical alignment and opposite the center of the roller and to provide the roller with corresponding central depressions which engage these respective teeth. Also it is preferable to provide spaces between the teeth 12 (or other portions of the roller) on the roller adjacent said depressions and the depressions 13—14 adjacent said teeth (10—11) on the carriage and car member, respectively. Such spaces permit unrestricted action of the teeth 12 (or other portion) on the roller through a predetermined lateral movement of the coupler. With such an arrangement of parts, the coupler (and carriage) is supported by the rollers entirely at the said central depressions when in normal central position and also during the predetermined amount of lateral movement (preferably in either direction) but upon any additional movement of the coupler its weight is entirely shifted to the teeth 12 on the roller adjacent the central depressions, thereby increasing the eccentricity of the load from its support and upon still further additional move-

ment the weight of the coupler is shifted to the tooth 15 whereby the eccentricity is still further increased.

In the preferred form two rollers are employed positioned equi-distant on either side of the center line of the coupler. However, only one roller may be used at one end of the carriage to return the coupler to its central position and any convenient means used to support the opposite end of the carriage or, a single roller may be positioned adjacent the center of the car and the extremities of the carriage otherwise supported to prevent the device from tipping.

15 I claim:

1. A centering device for a car coupler comprising a member provided with a rack, a coupler carriage provided with a rack, and an oval toothed roller engaging said treads with its minor axis positioned vertically when the coupler carriage is in normal position.
2. A centering device for a car coupler comprising a member provided with a rack, a coupler carriage provided with a rack, and an oval roller provided with teeth engaging said racks with its minor axis positioned vertically when the coupler carriage is in normal position.
3. In a railway car; the combination of a car part having a rack, a coupler carriage having a rack, and a toothed oval roller supporting the carriage upon the car part, the racks and teeth so arranged that oppositely disposed teeth engage oppositely disposed valleys so as to entirely support the carriage through a predetermined amount of movement of said carriage, said racks and teeth also so arranged that other teeth have unrestricted action through said predetermined movement which engage valleys between

other teeth and entirely support said carriage through any additional movement thereof whereby the eccentricity of the load from its support is increased.

4. In a railway car; the combination of a car part having a rack, a coupler carriage having a rack, and a toothed oval roller supporting the carriage upon the car part, the racks and teeth so arranged that oppositely disposed teeth engage oppositely disposed valleys so as to entirely support the carriage through a predetermined amount of movement of said carriage in either direction, said racks and teeth also so arranged that other teeth have unrestricted action through said predetermined movement in either direction which engage valleys between other teeth and entirely support said carriage through any additional movement thereof in either direction whereby the eccentricity of the load from its support is increased.

5. In a railway car; the combination of a car part element, a coupler carriage element, and a roller supporting said carriage upon said car part, said roller having surfaces entirely supporting said carriage through a predetermined amount of movement of said carriage, said roller also having a portion on each side of each end of said surfaces with unrestricted action through said predetermined movement, one of said portions at each end of the roller engaging said car part and carriage, respectively, and entirely supporting said carriage through any additional movement thereof in one direction, and the other of said portions engaging the car part and carriage, respectively, and entirely supporting said carriage through any additional movement thereof in the opposite direction.

ARTHUR E. SMALL.
